UNITED STATES PATENT OFFICE

2,542,249

TAPE-PULLING PLIERS

Arthur J. Higgins, San Diego, Calif.

Application July 17, 1947, Serial No. 761,721

3 Claims. (Cl. 81—5.1)

1

My invention relates to double action hand grips, and its purposes are to provide a hand operated grip for the use of engineers, surveyors, electricians or mechanics which can readily be applied to a chain, tape, wire or like object with even pressure thereon, and which can easily be released and slid to a new position thereon without being required to be released therefrom; to provide a double action spring grip with non-converging parallel gripping faces evenly applied to one of said objects with such leverage as to support the pull thereon under the usual conditions encountered in the art; to supply a grip which, while forming a firm attachment to said object, will not scratch, mar, deface or injure the surface thereof where the jaws of said grip are applied; to provide an adequate means for slidably guiding said object through the opening between the jaws of the grip when released therefrom and permitting without removal the said grip to be slid and successively clamped to said object for succeeding pulls thereon; to furnish a grip for said object which is contoured to fit the hand in the natural position that the said object would be held if grasped by the hand in the usual way and which is constructed to be handled in a similar manner; to guard against the grip becoming locked or jammed upon the said object so as to necessitate time and effort to remove the same therefrom; to render the parts readily accessible for inspection, adjustment, replacement or repair; and generally to provide a device which is strong and durable and not likely to get out of order. These and other purposes will appear from the drawing and as hereinafter set forth and described.

This invention is an improvement upon the chain or tape grip disclosed in my pending application, Serial No. 729,042, filed February 17, 1947, to which reference is made for a description of the more general features thereof.

Attention is hereby directed to the drawing, illustrating a preferred form of my invention, in which similar numerals of designation refer to similar parts throughout the several views and in which—

Figure 1 is a side elevation of my improved hand grip showing the jaws thereof open and in normal spaced position, and ready for application to the chain or tape upon insertion therebetween, and for gripping contact therewith upon compression of the handles of said grip;

Fig. 2 is a view of the handle end of device shown in Fig. 1 from line 2—2, looking in the direction of the arrows;

Fig. 3 is a view of the jaw end of said device,

from line 3—3, looking in the direction of the arrows, and

Fig. 4 is a side elevation similar to that shown in Fig. 1, showing the jaws thereof closed and in gripping contact with a section of said chain or tape, with the guiding latch swung to prevent sideways escape thereof.

Referring to the drawing, my improved hand grip 5 is shown as composed of two separate members 6 and 7; the member 6 having the handle 8, provided with the enlarged head 9 to which is pivotally secured by the round headed or countersunk screw 10, and rocking thereon, the detachable jaw 11; and the member 7, having the handle 12 integral with the jaw 13 which is pivotally connected to the head 9 by the round headed or countersunk screw 14. Preferably the portion of the shanks of both the screws 10 and 14 protruding from the head 9 are left unthreaded so that the jaws 11 and 13 respectively may turn freely thereon. The said jaws are constructed with opposing flat walls or planar surfaces to which are secured respectively in any suitable manner the sheet metal facings 11a and 13a, normally positioned so as to be in parallel relation one with the other, with a narrow passageway 15 in between, but located a sufficient distance apart so as to permit the ready introduction of a flat wire, tape or surveyor's chain 16 into said passageway and allowing the longitudinal sliding of the same therein.

For the purpose of securing the exact parallel occlusion of the facings 11a and 13a upon compression of the handles 8 and 12, the screw 10 passing through an opening provided therefor in the central outer portion of the rocking jaw 11, is so positioned in respect to the jaw 13 turning upon its fulcrum provided by the screw 14, that the said rocking jaw 11 will automatically upon said compression and contact with the wire or tape 16 always assume such relationship with the jaw 13 as to accomplish the said occlusion of said facings; the result following that because of the even pressure exerted by said facings a grip is accomplished which while forming a firm attachment to said wire or tape will not scratch, mar, deface or injure the same.

In order to prevent the sideways dislodgement or escape of the wire or tape from the passageway 15 between the jaws 11 and 13 once it is introduced therein, and to guide its longitudinal movement, I preferably employ the latch or catch 17, pivotally mounted upon the jaw 13 and positioned so as to be moved across a portion of the exposed open side of said passageway, and temporarily to close the same; the said latch being

provided with the finger hold 18 and the depression 19 extending through and projecting inwardly the wall thereof, and cuplike recesses 19a being formed in the adjacent wall of said jaw 13 or handle 12 and located to make locked spring engagement with the inward projection of said depression 19. In Fig. 1, the said latch 17 is shown in inoperative position before the introduction of the wire or tape in passageway 15, while in Fig. 4, it is shown in locked position after such introduction has taken place.

In order that the said passageway 15 may normally be open and the facings 11a and 13a kept apart in exact parallel relation for the introduction and sliding passage of the wire or tape 16, I preferably employ a special form of spring actuated plunger, comprising a rod 20 normally at right angles to said facing 11a, and having one end in threaded engagement with an opening provided therefor in the inner portion of the handle 8; the main portion of said rod extending inwardly through an opening in the extension 11b of the facing 11a and engaging with and passing through the screw-eye 21 secured to the wall of the handle 12, where the protruding other end of said rod is threaded to engage with the nut 22. Compression springs 23 and 24, mounted upon said rod and extending through the respective spaces between said handle 8 and extension 11b, and between said extension 11b and screw-eye 21, serving to keep said jaws 11 and 13 and the facings thereof apart except when said handles 8 and 12 are compressed against said springs to effect the desired grip upon the wire or tape. Preferably the rod 20 has welded or firmly secured thereto, adjacent to the extension 11b and normally in contact therewith, the collar 25, thereby limiting the rocking of the jaw 11 and upward movement of said extension 11b to a range not above the normal level thereof. Washers 26 and 27, contacting the ends of said springs 23 and 24 may be provided if desired.

The form, dimensions and character of my improved hand grip as shown in the drawing, are those preferred by me in the practice of my invention, but as is obvious could be varied without departing from the spirit or purpose thereof. Thus the length and turning arc of the handles 8 and 12, and the width of the gap between the jaws thereof, could be changed and adapted to meet the needs of the work to be performed by engineers, surveyors, electricians, mechanics and others, as required by them. Preferably all of the parts of my improved device are made of metal, but if desired any other suitable materials could be used.

To operate my improved hand grip, it is only necessary to introduce the tape or wire 16 into the passageway 15 as shown in the drawing, and to close the latch 17, at which time the said grip may be slid to any position desired on the tape or wire without removing the same therefrom; and at any time the grip may be clamped to said tape or wire by compression of the fingers and thumb of the hand to allow the same to be pulled; or upon release of such compression, again to open said grip. When the grip is no longer needed, it may readily be removed from the tape or wire by opening the said latch and by disengaging the tape or wire from the passageway 15.

Where in the claims, I have used the words "wire tape," I desire to be understood as meaning any form of metallic tape or wire upon which my improved grip could be used for pulling pur-

poses in the manner hereinbefore set forth, including surveyors' chains, engineers', mechanics' or electricians' tapes, wires or similar material.

My invention may be embodied in other specific forms without departing from the spirit or essential characteristics thereof. The present embodiment, as above set forth are therefore to be considered in all respects as illustrative and not restrictive, the scope of my invention being indicated by the appended claims rather than by the foregoing description, and all changes which may come within the meaning and range of equivalency of the claims are therefore intended to be embraced therein.

What I claim and desire to secure by Letters Patent is:

1. A double action hand grip, comprising two handle members, one of said members having an enlarged head and a rocking jaw pivotally mounted upon said head, the other member, having a jaw firmly secured thereto and being pivotally mounted upon said head; the said jaws mutually opposing each other and having their opposing faces unbrokenly flat and normally in open spaced parallel relation one with the other and forming a passageway therebetween for sliding engagement with a wire tape; and spring means associated with said handles for holding and maintaining said jaws in said normal spaced relation but permitting said jaws to make parallel engagement with said wire tape upon compression of said handle members.
2. The subject matter of claim 1, including a latch pivotally mounted upon one of said members and operable to close sufficiently the opening between said jaws at the sides thereof so as to guide the longitudinal movement and to prevent the lateral escape of said wire tape after being slidably installed as aforesaid.
3. A double action hand grip, comprising two handle members, one of said members having an enlarged head and a rocking jaw pivotally mounted upon said head to rock evenly in opposite directions, and other member having a jaw firmly secured thereto and being pivotally mounted upon said head; the said jaws mutually opposing each other and having firmly secured thereto sheet metal facings normally in open spaced parallel relation one with the other and forming a passageway therebetween for sliding engagement with a wire tape, one of the facings extending inwardly between said handle members beyond the opening between said jaws; and spring plunger means mounted upon said handle members and connected with said extended facings for holding and maintaining said jaws and facings in said normal spaced relation, but permitting said facings to make parallel engagement with said wire tape and to grip the same upon manual compression of said handle members.

ARTHUR J. HIGGINS.
